TOY BALLOON

Jesse C. Leas, Willow Grove, Pa.

Application May 18, 1956, Serial No. 41,547

Term of patent 3½ years

(Cl. D34—15)

Fig. 1 is a front elevational view of a toy balloon, showing my new design;

Fig. 2 is a side elevational view thereof;

Fig. 3 is a top plan view thereof; and

Fig. 4 is a rear elevational view thereof.

The characteristic features of my design are shown in full lines.

I claim:

The ornamental design for a toy balloon, substantially as shown and described.
